UNITED STATES PATENT OFFICE.

EDGAR D. MORSS, OF UNIONTOWN, PENNSYLVANIA.

GAS STOVE OR HEATER.

SPECIFICATION forming part of Letters Patent No. 734,732, dated July 28, 1903.

Application filed September 13, 1902. Serial No. 123,225. (No model.)

To all whom it may concern:

Be it known that I, EDGAR D. MORSS, a citizen of the United States, residing at Uniontown, in the county of Fayette and State of Pennsylvania, have invented a new and useful Improvement in Gas Stoves or Heaters, of which improvement the following is a specification.

This invention relates to an improved gas-stove; and it consists in the certain details of construction and combination of parts as will be fully described hereinafter.

In the accompanying drawings, Figure 1 is a central sectional elevation of my improved stove. Fig. 2 is a sectional plan view of the stove, the said section being taken on the line 3 3 of Fig. 1. Fig. 3 is a perspective view of the partition arranged at the rear by means of which the waste products of combustion are conducted to the chimney-flue. Fig. 4 is a perspective view of one of the triangular flues arranged side by side at the front of the stove and adapted to be covered with a coating of asbestos or mineral wool along their front or exposed surface.

To construct a gas-stove in accordance with my invention, I form from sheet metal the body portion of the stove 1, consisting of the side walls, the back, base, and rear wall, and a perforated top 2, the whole being formed somewhat in the shape of a rectangular box, as will be seen by reference to Fig. 1 of the drawings. Arranged at the open front of this stove and in parallel vertical lines are a series of angular tubes 8, each of which are formed from thin sheet metal, the acute angles of which are arranged in vertical lines in front for the purpose of forming a fire-board. Each of these exposed surfaces of the above-mentioned tubes 8 are fitted with an asbestos or mineral-wool covering 5 for a purpose well known in the construction of this class of stoves. Arranged at the rear of these above-mentioned angular tubes 8 is a partition-wall 10, extending from side to side and from a point near the base to the top 2. At the rear of this partition 10 is a flue 12, leading to the chimney or vent 13, the said flue being formed from sheet metal, (see Fig. 4,) 50 the same being riveted in a vertical position

to the rear wall 15 of the stove. Fitted at the front near the base and in a horizontal position are two brackets 6, used for the purpose of supporting a horizontal burner 7 of any desired form, but preferably of cylindrical form, having perforations on the inner side, whereby the admixture of gas and air are projected toward the fire-front 5.

In operation the gas entering the burner 7 through the mixer below is divided by the angular walls of the tubes 8 and by its combustion heats the angular tubes. The air circulating through the tubes from the base will gather heat and be discharged into the room through the perforations 3 at the top. 65 The waste products of combustion will pass through an opening 18 at the top of the partition 10 and pass downward, as indicated by the arrows, to the chamber 9, thence upward through the flue 12 to the escape 13. 70

It is obvious that various slight modifications and changes may be made in the general details of construction without departing from the spirit of the invention.

Having thus described my invention, what I claim, and desire to secure by Letters Patent, is—

1. In a gas-stove, the combination of a metal body comprising side walls, back, base, and rear wall, of a perforated top, a series of vertically-arranged tubes substantially triangular in cross-section, the front faces of said tubes being covered with a fireproof covering, a partition arranged between said side walls and being of less height than the length of 85 said tubes, a substantially U-shaped plate secured to the said back forming a flue therebetween, and a horizontally-arranged burner in front of said tubes, substantially as described. 90

2. In a gas-stove, the combination of a metal body, comprising side walls, back, base, and rear wall, of a perforated top, a burner, a series of vertically-arranged tubes substantially triangular in cross-section with their 95 inclined sides directed toward the said burner, said tubes being spaced apart, a covering for the front of said tubes, said covering arranged in the spaces between said tubes, a partition arranged between said tubes and said back 100

and being of less height than the length of the said tubes, a substantially U-shaped plate between said partition and said back, and being secured to said back, and plate being of less length than the height of said partition, substantially as described.

In testimony whereof I have hereunto

signed my name in the presence of two subscribing witnesses.

EDGAR D. MORSS.

In presence of—
LOUIS MOESER,
M. HUNTER.
